FIG. 8.

UNITED STATES PATENT OFFICE.

HERBERT H. STEELE, OF MARCELLUS, NEW YORK, ASSIGNOR TO THE MONARCH TYPE-
WRITER COMPANY, OF SYRACUSE, NEW YORK, A CORPORATION OF NEW YORK.

TYPE-WRITING MACHINE.

Specification of Letters Patent. Patented Jan. 26, 1915.

1,126,585.

Application filed November 11, 1911. Serial No. 659,676.

To all whom it may concern:

Be it known that I, HERBERT H. STEELE, a citizen of the United States, and resident of Marcellus, in the county of Onondaga and State of New York, have invented certain new and useful Improvements in Type-Writing Machines, of which the following is a specification.

My invention relates to what is commonly termed tally strip mechanism for typewriting machines and the general object of said invention is to provide novel and improved mechanism of the character specified.

More specifically my invention relates to improvements on the construction shown in my prior Patent No. 1,052,022, granted Feb. 4, 1913. In the prior construction aforesaid the tally feed roll and the tally clamp are mounted at opposite ends of a vibratory or rocking frame, which frame is automatically controlled so that the feed roll is moved into operative relationship with the tally strip when the tally strip is brought into the printing field during end-wise movements of the platen, the clamp concurrently releasing the tally strip. There was in the prior construction an intermediate position in the movement of the vibratory frame when neither the clamp nor the feed roller was operative on the tally strip and as the receiving tally spool or holder was under constant tension the result was a tendency to advance the tally strip when the frame was in this intermediate position and a consequent irregular line spacing movement of the tally strip. To remedy this defect I have provided a clamping device for the tally strip which is automatically controlled separately from the tally feed roll. Also various changes have been made for the purpose of modifying and improving in other respects the prior construction.

To the above and other ends my invention consists in the features of construction, combinations of devices and arrangements of parts hereinafter described and particularly pointed out in the claims.

In the accompanying drawings which illustrate one form of my invention applied to a Monarch typewriting machine, Figure 1 is a fragmentary front elevation of the upper part of a Monarch typewriter embodying my invention. Fig. 2 is a horizontal sectional view taken on a plane indicated by

the dotted line $x-x$ in Fig. 1 and looking in the direction of the arrows at said line. Fig. 3 is a fragmentary side elevation partly in section of the devices shown in Fig. 1 but showing some of the parts in different relationships. Fig. 4 is a view corresponding to Fig. 3 but omitting some of the parts shown in said figure and showing other parts in different relationships. Fig. 5 is a fragmentary transverse sectional view of the front clamping devices. Fig. 6 is a fragmentary top plan view partly in section showing the stationary cam and the coöperating engaging devices. Fig. 7 is a vertical sectional view taken transversely of the platen on a plane indicated by the dotted line $y-y$ of Fig. 1 and looking in the direction of the arrows at said line. Fig. 8 is a view corresponding to Fig. 7 but showing some of the parts in different relationships. Fig. 9 is a longitudinal sectional view of the tally receiving roll, said view being taken on a plane represented by the dotted line z in Fig. 3. Fig. 10 is a fragmentary front elevation partly in section of the tally feed roll and front clamping device. Fig. 11 is a perspective view of an element which serves both as a clip or attaching device for the tally strip and also as a severing device therefor.

In various views parts are omitted and parts are broken away. Also the escapement mechanism, printing instrumentalities and various other parts of the machine are omitted from the drawings, but are, or may be, of the ordinary construction found in the Monarch typewriter. It is further to be understood that while I have preferred to show my invention applied to a Monarch machine, yet, nevertheless, the principles of the invention are applicable to other styles of writing machines.

As appears in Figs. 1 and 3 the main frame of the machine comprises posts 1 supporting a top plate 2 from which rise standards 3 secured whereto are fixed track ways 4 grooved to receive anti-friction rollers 5 which also coöperate with a grooved slide or rear bar 6 comprised in a platen carriage or carrier which further includes end bars 7 and 8. A platen axle 9 is journaled on the end bars and carries a platen 10 provided with a line spacing ratchet wheel 11 with which coöperates a line spacing pawl 12 controlled by a handle or lever 13. Co-

operative with the platen are paper feeding devices comprising a main feed roller 14 mounted on pivoted spring pressed arms 15 and a secondary feed roller 16 mounted on similar arms 17. Said feed rollers coöperate with the platen to the left of the narrow work sheet or tally strip hereinafter described through openings in a main paper deflector (not shown), said deflector terminating at the rear below a paper table 19. The feed rollers 14 and 16 are adapted to be released by devices comprising a rock shaft 20 provided with lugs 21 which coöperate with projections 22 on the arms 15, throwing said arms downward and releasing the main feed roller, the lower ends of the arms 15 acting in turn to swing the arm 17 downward to release the feed roller 16. Means for rocking the shaft 20 for releasing purposes are best shown in Figs. 1, 7 and 8 and comprise a crank arm 23 secured to the left end of the rock shaft and pivotally connected with an arm 24 provided with a finger piece 25, said arm 24 being pivotally connected with an arm 26 pivoted at 27 to the end bar 7. The arms 24 and 26 constitute toggle elements which normally are in the relationship shown in Fig. 7. When the finger piece 25 is pulled forward as in Fig. 8, the toggle elements are straightened and the rock shaft 20 is turned to release the feed rollers 14, 16 and is locked to maintain said feed rollers in released position as in Fig. 8.

35 The mechanism as thus far described is common to the Monarch typewriter.

The right-hand platen head is in the present instance sunk flush with the end of the platen and is provided with an elongated hub 28 which abuts against a boss 8^a on the end bar 8 and is screwed or otherwise secured to the platen axle 9. The end bars 7 and 8 of the platen carrier support a rod or bar 29 which extends lengthwise of the platen above the same, corresponding to the usual paper finger rod. The rod 29 assists to support a detachable tally strip supporting frame comprising a side plate 30 having a hub 31 which fits over the rod 29 and is secured thereto by a removable pin 32. The lower portion of the plate 30 is provided with a hole which receives the hub 28, permitting the plate 30 to be contiguous to the right-hand end of the platen. Besides the plate 30 the frame further includes a side plate 33 spaced leftward from the plate 30 and connected thereto by cross rods 34 and 35. The frame comprising the plates 30 and 33 and the connecting rods 34 and 35 constitutes in effect a single member detachably supported on the platen carrier near the right-hand end of the platen so that the tally strip 36 carried by the tally strip frame may be fed around the right-hand end of the platen. Said tally strip is wound

in a roll as indicated at 37, and the roll is mounted to turn on a flanged support 38 secured to the upper, rearwardly, curved end of the side plate 30. The loose end of the tally strip 36 is drawn forward from the under side of the roll 37 as shown in Fig. 3 and is led down over the paper table 19 to the left of the plate 30, passing between said paper table and a guide plate 39 suitably secured to the rear face of the plate 30 and extending downward and forward, curving around the rear and under sides of the platen and terminating at the front side of the platen somewhat below the printing point. The guide plate 39 is arranged between both the paper table 19 and also a paper apron 40 which is hung or suspended loosely from the rock shaft 20 by clips 40^a (Fig. 4). Said apron curves around the platen and the guide 39 and terminates at the front of the platen just below the guide 39, the forward end of said apron resting normally on the bottom edge of a cut-out 41 formed at the right-hand end portion of the usual scale plate 42. The apron 40 is preferably a section separate from the body of the usual or main paper apron (not shown) which extends lengthwise of the platen and is spring pressed toward the same. The guide plate 39 coöperates with the paper table and paper apron to provide a slot, passage way or channel 43 through which the tally strip passes and by which it is guided around the platen, the guide plate 39 being interposed between the tally strip and the platen and holding the tally strip away from the platen until the tally strip approaches the printing point. The inner face of the tally strip 36 is preferably carbonized in two longitudinal fields, the left-hand being black carbon and the right-hand red. The guide 39 prevents the carbonized surface from off-setting on the bill sheet which underlies the tally strip but is separated therefrom by the guide 39, said bill sheet indicated in Fig. 4 by the numeral 44, passing between the platen and said guide. Furthermore, where the bill sheet is frequently inserted and removed from the machine in the course of being filled in, the guide 39 protects the sheet and also prevents it from being interfered with by the tally strip during such insertion and removal.

A tally strip guide is also provided in the vicinity of and above the printing point. Said guide comprises a plate 45 which curves from a point above the printing line rearward over the platen for a short distance and then inclines upward and rearward, its upper portion being provided with ears 46 secured by screws 47 to the sides of the detachable frame. Fingers 48 extend downward from the lower edge of the guide 45, said fingers crossing the printing line and their ends overlapping and engaging with 130

the upper edge portion of the guide plate 39. The work sheet 44 passes upward behind the fingers 48 and guide 45 while the tally strip overlies said fingers and the guide. In other words, the guide and fingers are interposed between the work sheet and the tally strip and with the guide plate 39 maintain or hold the tally strip away from the platen surface throughout its course around the platen. The guide plate 45, fingers 48 and the guide plate 39 provide an opening through which the types may print and through which the pressure roll for feeding the tally strip, as herein-after described, may coöperate with the platen above the printing line. After crossing the printing line the tally strip passes upward and rearward over the guide 45 to a holder on which it is wound. Said holder is shown in detail in Fig. 9 and comprises a tubular body portion 49 provided with heads 50 which bear on a shaft 51, the ends of said shaft being reduced and bearing in openings in the side plates 33 and 30. The right-hand reduced portion 52 is provided with a crank 53 by which the shaft may be turned. A coiled spring 54 surrounds the shaft 51 within the tube 49, one end of said spring being fixed to the shaft and the other end to the head 50, the spring tending constantly to turn the receiving holder so as to wind the tally strip thereon. The inner end of the tally strip is secured to the tube 49 by a spring clip 55 shown detached in Fig. 11 and attached in Fig. 1, said spring clip being provided with a finger piece 56 by which it may be removed or detached from the tube 49. Confined between the crank 53 and the outer face of the plate 30 is a ratchet wheel 57 provided with a slot 58 which is engaged by a pin 59 on the end 52, the construction maintaining the ratchet wheel against turning movement relative to the shaft 51. A gravity pawl 60 (Fig. 5) prevents the ratchet wheel from turning backward under the action of the spring 54 and the consequent weakening of said spring. By turning the handle of the crank 53 the tension of the spring 54 may be increased. The spring is regulated to take up the slack in the tally strip and so that as the tally strip is advanced or line spaced it will be correspondingly wound on the receiving roll. The device 55 may also be employed as a severing device to cut the tally strip at suitable intervals. To use the device in this way the wound portion of the tally strip is loosened from the receiving roll and the device 55 is removed therefrom and then replaced outside the tally strip and near the place where the tally strip is to be severed. Then by drawing the tally strip against the straight edge 55^a it may be readily cut off. It will be understood that the severed portion contains items

which are written on the outer face of the tally strip through the regular ribbon of the machine. The loose, newly severed end of the tally strip may be secured to the core 49 by the spring clip 55 before a new series 70 of printing operations is begun.

In my prior construction means are provided which coöperate with the platen to feed the tally strip when the platen is turned at such times as the tally strip is 70 within the printing field. Said means includes a pressure roll 61 (Fig. 10) mounted on a sleeve 62 bearing on a rod 63 which is comprised in a rocking frame that further includes parallel plates or levers 64, 80 the lower ends whereof are connected by and carry the rod 63. The upper arms of the levers 64 carry a cross rod 65 on which bears a sleeve 66, said sleeve as shown clearly in Fig. 5 being provided with a 85 plate 67 which with the sleeve 66 supports a triangular sheath 68 of rubber or the like which comprises with the plate 67 and the sleeve 66 a pivoted clamp coöoperative with the clamping device or plate 45 to clamp the 90 tally strip. The operative face of the clamp 66-68 is flat and inclines slightly to the relatively fixed part or coöperative clamping face 45 when the clamp is released, due to co-action with the cross rod 64; but when 95 the movement of the swinging frame on which said clamp is mounted brings it into engagement with the relatively fixed part 45, said clamp swivels or turns on its pivot 65 until it fully engages with the face of 100 the part 45 as shown in Fig. 5. The levers 64 are suitably secured to the reduced end portions of a sleeve 69, which sleeve in turn is secured by a screw 69^a to a fulcrum rod 70, the left end of said fulcrum rod being 105 supported on a socket piece 71 secured to the frame plate 33 (Fig. 10) while the right end of said fulcrum rod bears in the plate 30, the fulcrum rod serving as a rock shaft for the rocking frame. A spring 72 is 110 wound around the cross rod 65 and tends constantly to maintain the rocking frame with the clamp in operative position against the plate 45 and the pressure roll 61 released or separated from the platen. By rocking 115 the shaft 70 the clamping element 68 may be thrown off and the pressure roll concurrently thrown on. Automatic means for thus rocking the shaft comprise a crank arm 74 secured to the right-hand outer end of the shaft and overlying a nose 75 on the forwardly extending arm of a lever 76 fulcrumed at 77 on the plate 30, the lower arm of said lever extending downward outside said plate and terminating in a horizontal 120 ear 78 which carries a roller 79 (Fig. 6). A slot 76^a in the lower arm of the lever 76 co-operates with a guide screw 80 fixed to the plate 30 to guide the lever during swinging movements. The roller 79 is adapted to co- 125

operate with a cam bar 81 suitably secured 10 to the top plate 2 and extending in the direction of the carriage travel. The right-hand end portion 82 of the cam bar is inclined rearward, providing a cam surface 15 which is in the path of the roller 79 and operates during leftward movements of the platen to force the roll forward, swinging the lever 76 on its fulcrum and causing the 20 nose 75, acting against the crank arm 74, to swing the rocking frame to the Fig. 3 position, throwing off the clamp, and concurrently throwing the pressure roll 61 down into operative engagement with the 25 paper and platen so that if now the platen be turned for line spacing, said pressure roll will coöperate with the platen to advance the tally strip. The cam bar 81 is so located that the roller 79 will not engage it so long 30 as that portion of the bill sheet, which is to the left of the tally strip, is in the printing field of the types or opposite the printing point; but just as the left edge of the tally strip approaches the printing point the 35 roller 79 will engage the cam 82, operating the train of mechanism connected to said roller so that when the tally strip is brought opposite the printing point the pressure roller 61 will be in operative position and the clamp will be released or thrown off.

It will be understood that the pressure of the clamp 68 on the plate 45 lessens and becomes ineffective before the pressure roll 61 swings down into full engagement with the tally strip. Consequently the tally strip will be momentarily free, permitting the spring 54 of the receiving roll holder to wind up more or less of the tally strip before the pressure roll 61 becomes effective, thereby wasting the tally strip to a greater or less extent. To avoid this defect, I provide means comprising a clamping device which is normally effective to clamp the tally strip in advance of its passing the printing point, said clamping device remaining effective until after the pressure roller 61 has swung down into effective engagement with the tally strip and platen, after which said clamping device will be automatically released. Said clamping device in the present instance comprises an arm 83 of spring metal which, as shown in Figs. 1 and 2, is disposed longitudinally of the paper table 19 in rear of the same, the inner end of said arm 83 being riveted at 84 or otherwise secured to the paper table. The outer end of the arm 83 projects beyond the right-hand edge of the paper table and is fashioned into a finger piece 85 by which the spring arm 55 may be controlled by hand at will. The spring arm is provided with a forward offset 86 which is movable in a cut-out, opening or slot 87 in the paper table 19 and provides a support for a clamping pad or sheath 88 of rubber or the like which coöperates with

the rear face of the guide plate 39. The tally strip 36 passes downward behind the guide plate and between it and the pad 88 and the inherent tension of the spring arm 83 normally maintains the clamping pad 88 in clamping engagement with the tally strip which is effectively held against movement by the coaction between the pad and the back of the plate 39. A headed shoulder screw 89 passes through a slot 90 in the 75 arm 83 and is secured in the frame plate 30, said screw providing a stop to limit the rearward movement of the arm 83. Devices are provided for automatically swinging the arm 83 rearward and releasing the clamping 80 pad 88, said devices comprising a lever 91 fulcrumed at 77 outside the lever 76 and adjacent and parallel thereto, said lever 91 being provided at its upper arm with a rearwardly curving nose 92 which plays in 85 a slot 93 in the paper table 19 and terminates normally contiguous to the outer free end portion of the arm 83, as shown in Figs. 2 and 3. The lower arm of the lever 91 extends downward from the fulcrum screw 77 90 and is provided with a guide slot 94 which coöperates with the guide screw 80, said lower arm terminating at its rear in an angular extension or engaging device 95 which is designed to coöperate with the cam 82 and 95 the cam bar 81, being so timed that it will not reach the cam 82 until the roller 79 has ridden up on the bar 81, as shown in Fig. 6. Consequently the pressure roll 61 will be thrown down into effective engaging position, as shown in Fig. 3, while the clamping 100 pad or device 88 is still in normal position, clamping the tally strip 36 as shown in said figure. As leftward movement of the platen carriage continues, however, the device 95 will engage with the incline or cam 82 and the lever 91 will be swung on its pivot, causing the nose 92 to force the spring arm 83 rearward to throw off the clamping pad 88 as shown in Fig. 4. With 105 the clamping devices 68 and 88 inoperative and the pressure roll 61 operative as shown in Fig. 4, the tally strip will be advanced or line spaced whenever the platen is turned forward. During return movements of the 110 platen carriage to the right the engaging device 95 will ride down off the cam bar 81 and the inherent spring of the arm 83 will restore the clamp 88 to operation before the pressure roll 61 is released, the consequence 115 being that after said pressure roll is released by the disengagement of the roller 79 from the cam bar 81, the clamp 88 will be in operation to prevent any accidental advance or forward creeping of the tally strip 120 which might otherwise occur prior to the engagement of the forward clamp 68. It will be understood that with a clamping device like 88 in use at the rear or introductory 125 side of the platen, the forward clamp 68 may 130

be dispensed with but I prefer to retain this forward clamp and to use it in association with the pressure roll 61 and the rear clamp 88.

- 5 In addition to the paper feeding and controlling devices hereinbefore described for the main work sheet, which devices include the feed rolls 14, 16, additional devices are provided for co-operating with the main work sheet above the printing line and at the front of the platen, said additional devices comprising a paper finger 96 provided with ears 97 which slidably engage a rock shaft 98. Said paper finger extends downward and forward over the platen and is maintained in engagement therewith by a leaf spring 99 which may engage a feather 100 on the rock shaft 98, the ears 97 being formed with slots 101 which receive said feather 100 (Fig. 7). The rock shaft 98 is arranged above the platen and extends lengthwise thereof, the left-hand end of said shaft bearing in an arm 102 fixed to and extending forward from the rod 29 while the right-hand end of said rock shaft, as shown in Figs. 1 and 10, bears in the socket piece 71. Fixed to the left-hand end of the rock shaft outside the support 102 is a crank arm 103 which extends downward and rearward and is connected by a link 104 with a crank arm 105 projecting upward from the rock shaft 20. The crank arms 103 and 105 and the link 104 provide a connection between the rock shaft 20 and the rock shaft 98, such that when the finger piece 25 is pulled forward to release the feed rollers 14 and 16, it will also operate to rock the shaft 98 and swing the paper finger 96 away from the platen from the Fig. 7 to the Fig. 8 position. In order that this operation may be effective to entirely clear the platen surface and provide a free and unobstructed passage all the way around the platen, I provide for throwing off the usual card clamp 106 by the paper finger 96. Said card clamp has a fixed pivot 107 on the machine frame and is spring pressed toward the platen so that its upper edge portions 108 normally press against the platen or the paper thereon; but the paper finger 96 is adapted to slide underneath these edge portions during endwise movements of the platen and when said paper finger underlies said edge portions, as shown in Figs. 1 and 7, the rocking of the shaft 98 will be effective to overcome the spring 109 of the card clamp and to swing said clamp on its pivot 107 away from the platen to the Fig. 8 position. Preferably, of course, the platen is moved endwise to locate the finger 96 behind the card clamp 106 prior to the throwing off or releasing operation through the finger piece 25. However, should the releasing operation take place 65 while the finger 96 is clear of the card clamp
- said finger will be thrown outward to the dotted line position in Fig. 8 and at this time the finger will be entirely forward and clear of the ribbon mechanism of the machine so that the endwise movement of the carriage will not be obstructed by the interference of said paper finger with said ribbon mechanism.
- It will be understood that the main work sheet or sheets may be inserted in or removed from the machine at will without interfering with the tally strip which is superposed on the right-hand portion of the main work sheet when the latter is in position to receive type impressions. Said main work sheet may be advanced from line to line without interfering with the tally strip or moving the latter so long as the tally strip is not opposite the printing point. When the tally strip is brought opposite the printing point and the types are operated, the impressions through the usual inked ribbon will be made on the tally strip and transmitted from the carboned back of said strip to the main work sheet, so that the impressions will be duplicated on the tally strip and the main work sheet at a single operation. These duplicate impressions are usually totals relative to items which are specified on the left-hand edge portion of the main work sheet outside the field of the tally strip. The tally strip thus affords a check on the bill or items on the main work sheet. The use of the present invention insures that the items on the tally strip will be in condensed form since the tally strip is automatically advanced when the bill sheet is line spaced after the totals have been printed in duplicate on the tally strip and bill sheet, and since safety devices are provided which insure that the tally strip shall never be solely in the control of the spring take-up at the receiving roll. At other times, during the writing on the bill sheet at the left of the tally strip, line spacing operations of the bill sheet will not affect the tally strip.
- It will be noted that by my present invention I provide a platen in combination with a plurality of paper controlling devices, and means for automatically moving said devices successively into and out of operation, the movement of one device being completed before the movement of the other device begins; that in the present instance one of said devices is a paper feeding device or feed roller and another of said devices is a paper clamping device; that by moving the devices as specified, the construction assures that the feeding device operatively engages with the paper before the clamping device opens and releases the paper; that the clamping device normally cooperates with the paper while the feeding device normally is in inoperative position;

that a clamp is provided at the introductory or rear side of the platen and in advance of the printing point, that is, the clamp coöperates with the paper before the 5 paper reaches the printing point; that the last named clamp is operative, that is, it is opened and closed, independently of rotary movement of the platen; that it is opened or released during endwise movements of the platen by automatic means 10 comprising a cam bar and a swinging lever on the platen carriage; that the paper feeding device is at the opposite side of the platen, in the present instance the front or 15 delivery side; that the paper feeding device in the present instance is mounted on a rocking or swinging frame which also supports another clamping device, which other clamping device alternates in operation with 20 the feeding device or feed roll; that the means for automatically moving or operating the clamping device and the feed roll operate at predetermined points in the endwise travel of the carriage; that devices are 25 provided for insuring that the feeding device is operative before the clamping device at the rear of the platen is rendered inoperative; that these clamping and feeding devices are provided in the present instance 30 in connection with a tally strip mechanism; that the tally strip is provided with an automatic take-up, that is, the tally strip receiving roll is associated with spring means which tends constantly to wind the tally 35 strip on said roll; and that by providing a releasable clamp which normally prevents the take-up from operating, in association with a feed roll for feeding the paper in advance of and to said take-up and with 40 other means for insuring operative engagement of said device with the paper prior to the release of the clamp, the take-up or spring receiving roll is thereby prevented 45 from winding up the paper at times other than when such winding is desired. Further it will be noted that I provide a paper 50 controlling or feeding device, in the present instance a paper finger, on the carriage of the machine and a paper feeding device, 55 in the present instance a card clamp, on the frame of the machine in combination with means for releasing the paper feeding device on the carriage and concurrently releasing the paper feeding device on the frame of the machine.

Various changes may be made without departing from the spirit and scope of my invention.

What I claim as new and desire to secure 60 by Letters Patent, is:—

1. In a typewriting machine, the combination 65 of a platen, a plurality of paper controlling devices, and means for automatically moving said devices successively into and out of operation, the movement of one

device being completed before the movement of the other device begins.

2. In a typewriting machine, the combination 70 of a platen, a paper feeding device, a paper clamping device, and means for automatically moving said devices successively into and out of operative position, the movement of one device being completed before the movement of the other device begins.

3. In a typewriting machine, the combination 75 of a platen, a paper clamp comprising two co-acting members operative to clamp the paper between them at the introductory side of the platen, and automatic means for moving said clamp into and out of operative engagement with the paper, said means being rendered effective by traveling movements of said platen.

4. In a typewriting machine, the combination 80 of a platen, a paper clamp comprising two engaging members arranged at the rear of the platen, the paper passing between said members before reaching the printing point, and automatic means for moving one of said members into clamping engagement 85 with the other, said means being rendered effective by traveling movements of said platen.

5. In a typewriting machine, the combination 90 of a platen, a paper feeding device, a paper clamping device, and means for automatically moving said devices successively into and out of operative position, the movement of one device being completed before the movement of the other device begins, 100 said means operating automatically during endwise movements of the platen.

6. In a typewriting machine, the combination 105 of a platen, a paper feeding device, a paper clamping device, said devices being arranged at opposite sides of the platen, and means for automatically moving said devices into and out of operative position.

7. In a typewriting machine, the combination 110 of a platen, a paper feeding device, a paper clamping device, said devices being arranged at opposite sides of the platen, and means for automatically moving said devices into and out of operative position in alternation, the movement of one of said 115 devices being completed before the movement of the other device begins.

8. In a typewriting machine, the combination 120 of a platen, a paper feeding device, a paper clamping device, said devices being arranged at opposite sides of the platen, and means for automatically moving said devices into and out of operative position, said means operating during endwise movements 125 of the platen and independently of turning movements thereof.

9. In a typewriting machine, the combination 130 of a platen, a paper clamp operative independently of the platen to clamp paper at the introductory side of the platen in ad-

vance of the printing point, and means for moving said clamp into and out of operation, said means operating automatically during endwise movements of the platen 5 and as the result of such endwise movement.

10. In a typewriting machine, the combination of a platen, a paper feeding device, a paper clamping device, and means for automatically moving said devices successively into and out of operative position, the movement of one device being completed before the movement of the other device begins, said means operating automatically at predetermined points in the endwise travel 15 of the platen.

11. In a typewriting machine, the combination of a platen, a paper feeding device coöperative therewith to feed paper, a paper clamp coöperative with a part independent 20 of the platen to hold paper from being fed by the platen, and means for successively moving said device and said clamp into and out of operative position, the movement of one device being completed before the movement of the other device begins. 25

12. In a typewriting machine, the combination of a platen, a paper feeding device coöperative therewith to feed paper, a paper clamp coöperative with a part independent 30 of the platen to hold paper from being fed by the platen, and means for successively moving said device and said clamp into and out of operative position, the movement of one device being completed before the movement of the other device begins, said 35 means operating automatically at the predetermined points in the endwise travel of the platen.

13. In a front-strike typewriting machine, 40 the combination of a platen, a paper feeding device coöperative therewith above the printing point to feed paper, and a paper clamp operative automatically and independently of said paper feeding device to clamp paper before it reaches the printing point to prevent the advance of the paper over the printing point when the platen is turned.

14. In a front-strike typewriting machine, 45 the combination of a platen, a paper feeding device coöperative therewith above the printing point to feed paper, and a paper clamp operative to clamp paper before it reaches the printing point, so as to prevent the advance of the paper over the printing point when the platen is turned, the clamp being normally operative and the feeding device being normally in inoperative position. 55

15. In a front-strike typewriting machine, 60 the combination of a platen, a paper feeding device coöperative therewith above the printing point to feed paper, a paper clamp operative to clamp paper before it reaches the printing point, the clamp being nor-

mally operative and the feeding device being normally in inoperative position, and means operating first to move said feeding device into operative position and then to render said clamp inoperative. 65

16. In a typewriting machine, the combination of a platen, a paper feeding device, a paper clamp device, and means for automatically moving said devices into and out of operative position in alternation, said devices being so arranged as to insure that the feeding device is operative before the clamping device is rendered inoperative. 70

17. In a typewriting machine, the combination of a platen, an automatic take-up for paper fed around the platen, a releasable clamp normally preventing said take-up from operating, a device operative to feed the paper in advance of said take-up, and means for insuring operative engagement of 75 said device with the paper prior to the release of said clamp.

18. In a typewriting machine, the combination of a platen, a paper receiving roll holder, means tending constantly to turn 80 said holder to wind the paper thereon, a releasable clamp normally preventing the winding on of the paper, a device normally inoperative but adapted to coöperate with the platen to feed paper to said holder, and means for moving said device to operative position and for opening or releasing said clamp, the movement of said device ending before said clamp is released. 85

19. In a typewriting machine, the combination of a platen, a paper receiving roll holder, means tending constantly to turn said holder to wind the paper thereon, a releasable clamp normally preventing the winding on of the paper, a normally inoperative 90 paper feeding device adapted to engage the paper between said clamp and said holder, and means for rendering said device operative and for opening or releasing said clamp. 100

20. In a typewriting machine, the combination of a platen, a paper receiving roll holder, means tending constantly to turn said holder to wind the paper thereon, a releasable clamp normally preventing the winding on of the paper, a normally inoperative paper feeding device adapted to engage the paper between said clamp and said holder, and means for rendering said device operative and for releasing said clamp, said means insuring the operative engagement of 105 said device prior to the releasing movement of said clamp. 110

21. In a typewriting machine and in tally strip mechanism, the combination of a platen, a spring controlled tally strip take-up roll, a releasable clamp operative independently of the platen to normally clamp the tally strip, a device coöperative with the tally strip to feed the tally strip, and means for bringing said device into operative en- 115 120 125 130

22. In a typewriting machine, the combination of a platen, a paper guide providing a passage-way or channel for guiding paper at the introductory side of the platen, a clamp removable transversely through said passage-way and coöperative with one side of said guide to normally clamp the paper, automatic means for moving said clamp into and out of operation, and means for feeding the paper when said clamp is opened or released.
23. In a typewriting machine, the combination of a platen, a spring arm provided with a paper clamping pad, said pad normally coöperating with a part independent of the platen to clamp paper, pressure roll devices, and means independent of said pressure roll devices for moving said spring arm to release the paper from the grip of said pad.
24. In a typewriting machine, the combination of a platen, a spring arm provided with a clamping pad, said pad normally coöperating with a part independent of the platen to clamp paper, and means for moving said spring arm to release the paper from the control of said pad, said means comprising a lever and a cam operative on said lever during the letter space traveling movements of the platen.
25. In a typewriting machine, the combination of a platen, a spring arm provided with a clamping pad, said pad normally coöperating with a part independent of the platen, and automatic means for moving said spring arm to release the paper from the grip of said pad, said means comprising a lever and a cam operative on said lever during the letter space traveling movements of the platen, said spring arm being also releasable at will by a hand operation independent of said lever.
26. In a typewriting machine, the combination of a platen, two parallel guide plates between which the paper is guided, one of said plates being slotted, and a spring arm mounted on said slotted plate and provided with a pad, said pad protruding through the slot in said plate and normally engaging the other of said parallel plates to clamp paper.
27. In a typewriting machine, the combination of a platen, an inclined paper table at the introductory side of the platen, said paper table being provided with an opening, a supplementary guiding plate parallel with and forward of said paper table, and a spring arm on said paper table provided with a paper clamping pad protruding through the opening therein and engaging operatively with the supplementary guiding plate.
28. In a typewriting machine, the combination of a platen, a rocking frame, a paper feeding device on said frame, a paper clamp on said frame, a fixed part with which said clamp coöperates, said clamp being pivoted on said frame and having a swiveling action with respect to said fixed part during the rocking movement of said frame, and means for rocking said frame.
29. In a typewriting machine, the combination of a platen, a rocking frame, a paper feeding device on said frame, and a paper clamp on said frame, said paper clamp being pivoted to said rocking frame and being provided with a flat face coöperative with a relatively fixed part, the clamp being free to turn on its pivot during the rocking movement of said frame.
30. In a typewriting machine, the combination of a platen, a rocking frame, a paper feeding device on said frame, a paper clamp on said frame, automatic means for rocking said frame to move said devices alternately into and out of operation, a second clamp, and means operating automatically to move said second clamp into and out of operation.
31. In a typewriting machine, the combination of a platen, a rocking frame, a paper feeding device on said frame, a paper clamp on said frame, automatic rocking means for rocking said frame to move said devices alternately into and out of operation, a second clamp, and moving means operating automatically to move said second clamp into and out of operation, said rocking means and said moving means being timed so that the movement of said rocking frame is completed prior to the beginning of movement of said second clamp.
32. In a typewriting machine and in tally strip mechanism, the combination of a platen, a receiving roll holder tending constantly to wind the tally strip thereon; a rocking frame provided with a tally feeding device and a tally clamping device; automatic means for rocking said frame to move said devices alternately into and out of operation, said automatic means comprising a lever and a cam bar on the frame of the machine; a second tally strip clamp normally operative; and automatic means for releasing said second clamp comprising a second lever coöperative with said cam bar.
33. In a typewriting machine and in tally strip mechanism, the combination of a platen; a platen carrier; a tally strip receiving roll holder on said carrier; a spring tending constantly to turn said roll holder to wind the tally strip thereon; a rocking frame carrying a clamp normally coöperative with a fixed part to clamp the tally strip, a normally inoperative pressure roller on said rocking frame; means operating automatically to rock said frame to release said clamp and bring said pressure roller into coöperation with the platen, said means

comprising a lever on the carriage and a cam bar fixed to the frame of the machine; a second clamp normally operative on the tally strip at the opposite side of the platen from said swinging frame; and automatic means for releasing said second clamp comprising a second lever coöperative with said cam bar.

34. In a typewriting machine and in tally strip mechanism, the combination of a platen; a platen carriage; a tally strip receiving roll holder on said carriage; a spring tending constantly to turn said roll holder to wind the tally strip thereon; a rocking frame carrying a clamp normally coöperative with a fixed part to clamp the tally strip; a normally inoperative pressure roller on said frame; means operating automatically to rock said frame to release said clamp and bring said pressure roller into co-operation with the platen, said means comprising a lever on the carriage and a cam bar fixed to the frame of the machine; a second clamp normally operative on the tally strip at the opposite side of the platen from said rocking frame; and automatic means for releasing said second clamp comprising a second lever coöperative with said cam bar, the two levers being so related that the movement of the swinging frame is completed before the second lever engages with the cam bar.

35. In a typewriting machine and in tally strip mechanism, the combination of a platen carriage, a platen, a tally strip supporting frame on said carriage, a paper table, a paper apron, a guide at the rear of the platen for separating the tally strip and main work sheet, said guide being secured to the supporting frame and coöperating with said paper table and said paper apron to provide a passage for the tally strip, and a second guide at the front of the platen, said second guide comprising a cross plate and depending parallel fingers extending transversely of the printing line and overlapping the first named guide.

36. In a typewriting machine and in tally strip mechanism, the combination of a platen carriage; a platen; a tally strip supporting frame on said carriage; a paper table; a paper apron; a guide at the rear of the platen for separating the tally strip and main work sheet, said guide coöperating with said paper table and said paper apron to provide a passage for the tally strip; a second guide at the front of the platen, said second guide comprising a cross plate, and depending parallel fingers extending transversely of the printing line and overlapping the first named guide; and a feeding device for the tally strip coöperative with the platen between said fingers.

37. In a typewriting machine, the combination of a platen, a platen carriage, a

paper controlling device coöperative with the platen and mounted on said platen carriage, a second paper controlling device mounted independently of the carriage, and means for concurrently releasing both said paper controlling devices, said means acting directly on one of said paper controlling devices which in turn acts to release the other paper controlling device.

38. In a typewriting machine, the combination of a platen, a platen carriage, a paper controlling device coöperative with the platen and mounted on said platen carriage, a second paper controlling device mounted on the frame of the machine, and means for concurrently releasing both said paper controlling devices, said means acting directly on one of said paper controlling devices which in turn acts to release the other paper controlling device.

39. In a typewriting machine, the combination of a platen, a platen carriage, a paper controlling device coöperative with the platen and mounted on said platen carriage, a second paper controlling device mounted on a fixed part, and manual means on the carriage operative to release both said paper controlling devices, said manual means acting directly on the paper controlling device that is mounted on the platen carriage, which device in turn acts on said second paper controlling device to effect the release thereof.

40. In a typewriting machine, the combination of a platen, a platen carriage, paper feeding devices thereon, a spring pressed card clamp pivotally mounted on the frame of the machine, and means on the carriage for releasing both said paper feeding devices and said card clamp, certain of said paper feeding devices acting when released directly on said card clamp to effect the release of said clamp.

41. In a front-strike typewriting machine, the combination of a platen, a platen carriage, a paper finger pivotally supported on the carriage and coöperative with the front face of the platen, a card clamp pivoted on the frame of the machine and normally spring-pressed into engagement with the front face of the platen, and manually controlled means for releasing said paper finger, said paper finger operating when released to release said card clamp.

42. In a typewriting machine, the combination of a carriage, a platen thereon, a main feed roller on said carriage, a paper finger on said carriage, a card clamp on the frame of the machine, said feed roller, paper finger and card clamp normally coöperating with the platen, and means for concurrently releasing the feed roller and the paper finger, the paper finger acting on said card clamp to effect the release thereof.

43. In a typewriting machine, the combi-

nation of a carriage, a platen thereon, a main feed roller on said carriage, a paper finger on said carriage, a card clamp on the frame of the machine, said feed roller, paper finger and card clamp normally coöperating with the platen, and means for concurrently releasing the feed roller, the paper finger and the card clamp, said means comprising a rock shaft provided with releasing devices, manually controlled toggle elements for turning said rock shaft, and a

second rock shaft supporting said paper finger and connected to said first rock shaft by crank arms and a link.

Inventor at Syracuse, in the county of Onondaga, and State of New York, this 9th day of November, A. D. 1911.

HERBERT H. STEPHEN.
